UNITED STATES PATENT OFFICE.

HENRY SAMUEL ESCH, OF NEW YORK, N. Y., ASSIGNOR OF ONE-HALF TO
NICHOLAS P. VALERIUS, OF CHICAGO, ILLINOIS.

AUTOMATIC TRACK-SWITCH FOR ELECTRIC RAILWAYS.

SPECIFICATION forming part of Letters Patent No. 690,256, dated December 31, 1901.

Application filed April 26, 1901. Serial No. 57,570. (No model.)

To all whom it may concern:

Be it known that I, HENRY SAMUEL ESCH, a citizen of the United States, and a resident of the city of New York, borough of Manhattan, in the county and State of New York, have invented a new and Improved Automatic Track-Switch for Electric Railways, of which the following is a full, clear, and exact description.

The invention relates to devices for shifting the switch in the track of an electric railway to run a car either upon a branch line or continue it on the main line.

The object of the invention is to provide a new and improved automatic switch completely under the control of the motorman to enable the latter to run the car in the desired direction, the means employed for the purpose mentioned being very simple and durable in construction and not liable to get out of order in any kind of weather.

The invention consists of novel features and parts and combinations of the same, as will be fully described hereinafter and then pointed out in the claims.

A practical embodiment of the invention is represented in the accompanying drawings, forming a part of this specification, in which similar characters of reference indicate corresponding parts in all the views.

Figure 1 is a diagrammatic view of the improvement. Fig. 2 is an enlarged longitudinal sectional elevation of the trolley-wire attachment. Fig. 3 is a transverse section of the same on the line 3 3 in Fig. 2. Fig. 4 is a similar view of the same on the line 4 4 in Fig. 2. Fig. 5 is a like view of the same on the line 5 5 in Fig. 2. Fig. 6 is a similar view of the same on the line 6 6 in Fig. 2.

As shown in Fig. 1, the feed-line is indicated by the letter A, and the trolley-wire B carries an attachment C, arranged somewhat at the rear of the switch-point D', for connecting the main track D with a branch track D² whenever a car is to travel from the main line to the branch line, as hereinafter more fully described, it being understood that the switch-point D' is normally closed to render the main track continuous. The attachment C is carried by and incloses a portion of the trolley-wire B, and said attachment consists of metallic end pieces C', engaged on the un-

der side, at the outer ends, by the trolley-wire B, the latter then passing through inclined openings C² in an upward direction and into longitudinally-apertured pieces C³, made of fiber or other suitable insulating material and riveted or otherwise fastened to the end pieces C'. Each of the pieces C³ is preferably made in sections fastened together by screws, as shown in Fig. 5. The trolley-wire passes longitudinally through the insulating-pieces C³ and then through a rubber or similar tube C⁴, having its reduced ends fitted into corresponding bores in the adjacent inner ends of the pieces C³, so that that portion of the trolley-wire B in the end pieces C³ and the tube C⁴ is completely insulated. The insulating-pieces C³ have their inner ends connected with each other at the bottom by a metallic U-shaped bar C⁵, preferably made of copper, but insulated from the end pieces C' by the pieces C³ to prevent arcing when the trolley-wheel passes from the end piece to the bar C⁵. On the bar C⁵ are fitted or otherwise secured a number of clamps E, one of which is engaged by a wire F, leading to a switch-point shifting or actuating device G, preferably of the construction shown and described more fully in my application for Letters Patent of the United States, Serial No. 57,569, filed of even date herewith. This switch-point-shifting device is connected by a link H with the switch-point D', and when a current is sent by the above-described arrangement to the said shifting device G then the switch-point is shifted from a closed position into an open position, and when a second current is passed to the said device G then the switch-point is moved back to its former closed position. The shifting device G is connected by a wire F' with the feed-line A or with any other source of electric supply, and in the wires F F' is preferably arranged a fuse-box F² for preventing destruction of the electromagnet in the device G in case of an overcharged current. The trolley I, engaging the trolley-wire B, is connected in the usual manner with the controller J, connected with a motor K, connected with the car-axle and wheels L, traveling on the track, to make electric connection with the ground.

The operation is as follows: When the car

travels in the direction of the arrow a' and the trolley I passes from the trolley-wire B upon the metallic end pieces C', it leaves the trolley-wire B and then passes onto the insulating-piece C³ and finally passes upon the metallic bar C⁵, so that the circuit for the shifting device G is completed, and the switch-point D is shifted to open the main track to the side track D² for the car to pass upon the branch line. If the next following car is intended to continue on the main line, then the above-described operation is repeated—that is, a current is sent to the shifting device G, and the latter shifts the switch-point back to its former position to render the main track continuous. Now in case the next car is also to continue on the main line then the motorman simply opens the controller S at the time the trolley I leaves the trolley-wire B to pass upon the attachment C, so that the circuit for the shifting device G is not closed when the trolley-wheel passes upon the bar C⁵. Thus when this takes place the circuit for the said device G is not closed, and consequently the switch-point D' remains in a closed position and the main track A remains continuous, so that the car proceeds on the main line. By separating the metallic end pieces C' and the bars C⁵ by the insulating material C⁸ it is evident that the current from the trolley-wire B to the car and motor is completely cut off, and when the trolley I passes upon the metallic bar C⁵ a proper ground connection is had as long as the controller J is closed to insure proper working of the shifting device G, and thereby open the main track D to the branch track D² or close the latter to the main track, as previously described. It is understood that when the controller J is closed and the trolley I is in contact with the bar C⁵ then the return current from the shifting device G is by way of the wire F, clamp E, bar C⁵, trolley I, controller J, motor K, car axle and wheels L, and track to the ground.

No resistance is provided in the shunt made by the wires F F', as the motor upon the car is provided with a proper resistance which is always in the circuit at the moment when the shunt is traversed by the current.

In order to bring the underside of the attachment C in alinement with the trolley B, the outer portions of the end pieces C' are formed with bottom grooves C⁶ to receive the trolley-wire, as will be readily understood by reference to Figs. 2 and 4. By inclosing a portion of the trolley-wire in the attachment C it is evident that no electrical connection is possible between the trolley-wire and the trolley-wheel as long as the latter travels on the bar C⁵, and hence the device will work equally well in dry or rainy (sleet) weather. The lower portion of the attachment has a cross-section corresponding to the groove in the trolley-wheel, so that there is no danger of the trolley-wheel leaving the attachment

and rendering the device ineffective, as is so frequently the case with devices heretofore constructed. By engaging the trolley-wire in the grooves C⁶ and then bending it upward and passing it through the apertures C² and into the insulating-pieces C³ and through the tube C⁴, it is evident that the attachment is secured to the trolley-wire and no further fastening means are required, it being understood that the bent portions of the trolley-wire at the apertures C² prevent longitudinal movement of the attachment as well as side-wise motion or tipping over. Thus the attachment always stands in proper position for engagement by the trolley-wheel without jar or jerk, as the under side of the attachment is in alinement with the trolley-wire, and as the said under side also conforms to the shape of the groove of the trolley-wheel the attachment cannot tip over or the trolley-wheel jump off. By the arrangement described no transverse braces or like supports are required for holding the attachment C in position. The attachment C is located sufficiently far away from the switch for the motorman to have plenty of time to bring the car to a standstill in case he fails to properly set the controller J.

Having thus fully described my invention, I claim as new and desire to secure by Letters Patent—

1. An operating device for track-switches, comprising a frame provided with a bow-shaped channel, to receive a short portion of the trolley-wire and to maintain a bow-shaped loop in the same, a contact-plate located in said loop, in alinement with the general direction of the trolley-wire and insulated from the same, and an electrode for connecting said contact-plate with electrical mechanism for operating the switch, another electrode being the trolley of the car.

2. An operating device for track-switches having a wire attachment, comprising an insulating-frame for inclosing a part of the trolley-wire and forming in the same a bow-shaped loop, a contact-plate located in the said loop in alinement with the general direction of the trolley-wire so as to form therewith a straight surface to be engaged by the trolley, said contact-plate being insulated from the said trolley-wire and provided with an electrode, the trolley of the car constituting another electrode.

3. A trolley-wire attachment for track-switches, comprising a longitudinal frame provided with a sinuous channel for receiving a short part of the trolley-wire and thereby forming the same into a bow-shaped loop, and a contact-plate sunken in the said frame and located between the ends of the said loop, said contact-plate and the adjacent portions of the frame being in alinement with the general direction of the trolley-wire and both together forming therewith a straight surface to be engaged by the trolley, said contact-

plate being provided with a stationary electrode, another electrode being the trolley-wheel and its connections.

4. A trolley-wire attachment for track-switches, comprising a longitudinal frame provided with a sinuous channel for receiving a short part of the trolley-wire and thereby forming the same into a bow-shaped loop, and a contact-plate secured to the said frame between the ends of said loop and bent into conformity with the groove of a trolley-wheel so as to form a suitable track for the same, said contact-plate being provided with an electrode, and being insulated from the trolley-wire, and being in line with the general direction of said trolley-wire, so as to form therewith a straight surface of the general conformation suitable for engagement by a grooved trolley-wheel.
5. An operating device for track-switches, having a trolley-wire attachment, comprising metallic end pieces having longitudinal grooves in their bottoms, apertures for the passage of the trolley-wire, insulating-pieces secured to the end pieces and having longitudinal bores for the passage of the trolley-wire, an insulating-tube connecting said insulating-pieces with each other and through

which extends the trolley-wire, and a metallic bar for connecting said insulating-pieces with each other independent of the end pieces, said bar being adapted to connect with a return-wire, as set forth.

6. An operating device for track-switches, having a trolley-wire attachment, comprising metallic end pieces having longitudinal grooves in their bottoms, apertures for the passage of the trolley-wire, insulating-pieces secured to the end pieces and having longitudinal bores for the passage of the trolley-wire, an insulating-tube connecting said insulating-pieces with each other and through which extends the trolley-wire, a U-shaped metallic bar secured to said insulating-pieces at their inner or adjacent ends and independent of said end pieces, and a clamp held on said metallic bar, for engagement by a return-wire, as set forth.

In testimony whereof I have signed my name to this specification in the presence of two subscribing witnesses.

HENRY SAMUEL ESCH.
